CLAIM

The ornamental design for a multiple compartment trash container, as shown and described.

DESCRIPTION

FIG. 1 is a top and front perspective view of a multiple compartment trash container showing our new design, the top portion of the container being elevated with one lid of the container in an open condition for clarity of illustration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIG. 2

FIG. 3
